United States Patent Office

Des. 228,681

Patented Oct. 16, 1973

228,681

STILL CAMERA OR THE LIKE

Samuel F. Swayze, Rochester, N.Y., assignor to Eastman
Kodak Company, Rochester, N.Y.

Filed Aug. 2, 1972, Ser. No. 277,431

Term of patent 14 years

Int. Cl. D16—01

U.S. Cl. D61—1 B

FIG. 1

FIG. 1 is a front, top, and right side perspective view of a still camera or the like showing my new design; and FIG. 2 is a rear, bottom, and left side perspective view thereof.

I claim:

The ornamental design for a still camera or the like, as shown.
